UNITED STATES PATENT OFFICE.

PETER A. SOLEM, OF CINCINNATI, OHIO, ASSIGNOR TO J. A. FAY & EGAN COMPANY,
OF CINCINNATI, OHIO, A CORPORATION OF WEST VIRGINIA.

PLANING-MACHINE.

1,073,300.

Specification of Letters Patent. Patented Sept. 16, 1913.

Application filed May 29, 1913. Serial No. 770,715.

To all whom it may concern:

Be it known that I, PETER A. SOLEM, a citizen of the United States, residing at Cincinnati, in the county of Hamilton and State 5 of Ohio, have invented certain new and useful Improvements in Planing-Machines, of which the following is a specification.

My invention relates to planing machines arranged for planing wood.

10 It is the object of my invention to provide novel means for adjusting either end of the lower cutter-head support up or down independently for alining the lower cutter-head with the material support, and for simultaneously adjusting both ends of the lower cutter-head support to elevation with relation to the material support; and, further, to provide novel means for clamping the cutter-head support in adjusted positions.

15 The invention will be further readily understood from the following description and claims, and from the drawings, in which latter:

Figure 1 is an end elevation of my improved device. Fig. 2 is a vertical section of the same, taken on the irregular line 2—2 of Fig. 1. Fig. 3 is a cross-section of the same, taken on a line corresponding to the line 3—3 of Fig. 2. Fig. 4 is a horizontal section of the same taken on the irregular line 4—4 of Fig. 1. Fig. 5 is an enlarged sectional detail, showing the adjusting means for the cutter-head support, taken on the line 2—2 of Fig. 1; and, Fig. 6 is a rear 30 perspective view of the cutter-head saddle.

35 11 represents the frame of a wood planing machine, which may be of suitable construction, and have one or more horizontal cutter-heads and suitable upright cutter-heads and feeding devices mounted therein, the feeding device being arranged to feed the material in the direction of the arrow *a*.

12 represents a lower cutter-head.

13 is a material supporting table in advance of the lower cutter-head, which may be provided with any suitable adjusting means (not shown) for lowering or raising the table and adjusting the same toward and from the lower cutter-head in suitable 45 manner.

14 is a material supporting table in rear of the lower cutter-head.

The lower cutter-head shaft is mounted on

and adjustable with a support by which its position is determined with relation to the 55 material supporting parts in the machine, and novel means are provided for clamping the support in place after adjustment. The support in the present exemplification comprises a plurality of parts, exemplified as a 60 yoke and a saddle. The lower cutter-head is rigid with a shaft 15 having suitable driving pulleys 16 thereon and journaled in bearings 17. The bearings are shown on a yoke 18 longitudinally slidable crosswise of the 65 main frame of the machine and guided by a guide 19 on a saddle 20.

I provide novel means for adjusting either end of the lower cutter-head up or down, so as to aline the lower cutter-head with the 70 material supporting face of the material supporting part of the machine, so arranged that either end of the lower cutter-head may have adjustment imparted thereto without adjusting the other end thereof, so that if 75 only one end of the lower cutter-head is in incorrect position, the incorrect end only need be adjusted into correct position, and for simultaneously adjusting both ends of the alined cutter-head up or down so as to 80 bring the same to proper elevation with relation to the material supporting part of the machine. The cutter-head yoke is provided with side guide-faces 21, 22, which coact respectively with side guide-faces 23, 24, on a 85 rigid part of the frame. The cutter-head saddle is provided with side guide-faces 25, 26, which coact with the side guide-faces 23, 24. Portions of the side guide-faces 25, 26, are on depending cheeks 27, 28. Portions of 90 the side guide-faces 23, 24, are on cheeks 29 on the rigid part of the frame, the cheeks 27 coöperating with the cheeks 29. These guide-faces position the cutter-head yoke and saddle laterally for correctly positioning the same lengthwise of the main frame.

For maintaining the lower cutter-head support in longitudinal position, that is, in correct crosswise relation with the main frame, and permitting ready raising and 100 lowering of either end of the support throughout its various height positions, I provide a guiding slot 35, shown in one of the cheeks 29, with which a positioning pin 36 secured in one of the cheeks 27 coöperates, 105 the portion of the pin received in said slot

filling the space between the walls of said slot, thereby endwise positioning the lower cutter-head support, permitting tilting thereof during adjustment, and enabling either end thereof to be raised or lowered independently.

37, 38, are adjusting screws at the respective sides of the main frame corresponding to the respective ends of the lower cutter-head support. These adjusting screws are respectively journaled in bearings 39, 40, on the main frame and held endwise therein between collars 41 and gears 42, 43, shown as worm-wheels, on said respective screws. The said adjusting screws respectively have threaded connections with the saddle in threaded bearings 44, 45, in said saddle.

46, 47, are gears, shown in the form of worms, with which the respective worm-wheels 42, 43, coöperate. The worm 46 is fast on a hollow shaft 48 which is journaled in a bearing 49 in the main frame. A hand operating device 50, shown as a hand wheel, is on the hollow shaft. The hollow shaft is held endwise in the bearing 49 by the hub of said hand-wheel and a shoulder 51 on said hollow shaft. One end of a shaft 52 passes through the bore of the hollow shaft. Each of these shafts is rotatable with relation to the other of said shafts. The other end of the shaft 52 is journaled in a bearing 53 in the frame. The shaft 52 has the worm 47 fast thereon. The shaft is held endwise by having the worm 47 received against the bearing 53 and being provided with a shoulder 54 received against the hollow shaft 48. A hand operating device 55, shown as a hand-wheel, is on the shaft 52 for rotating the same.

Either shaft may be rotated independently for adjusting either end of the lower cutter-head to elevation, and slight axial movement is permitted between the operating devices for the respective adjusting screws for placing said operating devices in independent or rigid relations. For this purpose the hand-wheel 55 has spline connection 56 with the shaft 52.

50 A friction clutch 61 is located between the hand-wheel 55 and the hollow shaft 48, shown as a frusto-conical friction clutch, brought into clutching relation by endwise movement between the hand-wheels. One 55 of the clutch-members is shown on the hub of the hand-wheel 55, the other member thereof being shown formed in the end of the hollow shaft. This endwise movement is shown effected by a hand-wheel 62, having threaded connection with the reduced threaded end 63 of the shaft 52, the hub 64 of the hand-wheel 62 being arranged to be pressed toward the hand-wheel 55 for bringing the friction clutch 61 into clutching engagement, the turning of the hand-wheel 62

for effecting this clutching engagement urging relative axial movement between said hand-wheel and hollow shaft, and thereby connecting the same rigidly, so that when said clutch is in engagement the worms 46, 47, will be rotated simultaneously upon the rotation of either of the hand-wheels 50, 55. When said clutch is in disengaged relation, effected by rotation of the hand-wheel 62 in the opposite direction, either end of the cutter-head support may be raised or lowered independently of the other end of said support, so that if either end of the cutter-head is out of correct elevation with relation to the plane of the supporting surface of the material support, that end only need be raised or lowered, or either end of the cutter-head may be raised or lowered independently of the other, for positioning the cutter-head in alinement with the material supporting surface of the material support, so that when said cutter-head is in alinement but at incorrect elevation, the clutch 61 may be brought into clutching relation for simultaneously moving both ends of the cutter-head up or down into proper elevation.

80 The clamping mechanism which I employ for clamping the cutter-head support in adjusted position preferably acts upon the 95 part of the support in which the cutter-head is journaled, and is exemplified as comprising a pair of wedges 71, 72, acting with a clamping action upon the respective ends of the cutter-head support and operated by 100 means of a single shaft 73, the wedge-faces of said wedges at the respective ends of said cutter-head support slanting in directions opposite to each other, and the longitudinal positions of said wedges being unfixed, so 105 that the wedging action of one of said wedges will be dependent on the wedging position of the other of said wedges. Thus the operating shaft is provided with threaded portions 74, 75, forming respectively 110 right and left hand screws, with which respectively the corresponding threaded bores 76, 77, in said wedges coact. The wedges are located in recesses 78, 79, in a rigid part of the frame, the said recesses being provided with oppositely sloping wedge-faces 80, 81, with which wedge-faces 82, 83, of said wedges coact. Contact faces 84, 85, of said wedges are presented to the coacting face 21, of the cutter-head support. These 120 contact and coacting faces are preferably parallel with each other and with the guide between the cutter-head yoke and the cutter-head saddle, so that wedging between the wedges and said rigid part of the frame 125 and cutter-head yoke may be effected irrespective of the longitudinal position of the cutter-head yoke on the cutter-head saddle, or the position to which either end or both ends of said cutter-head yoke may be ele- 130

vated, and for permitting lengthwise shifting of said yoke upon very minute disengaging movement between said wedges.

The shaft 73 is provided with suitable turning means, exemplified as a pin 86, a suitable turning device, such as a crank, being arranged to be received over the end of the shaft and to make engagement with said pin for turning said shaft. The clamping shaft 73 is provided with collars 87, 88, fast thereon, normally spaced from a bearing 89 on the frame in which said shaft rotates. If either wedge should become lodged prior to its clamping action, one of said collars will engage the bearing for preventing undue axial movement of the clamping rod in either direction and avoiding turning of either screw thereon out of the threaded bore of either wedge.

The wedging action of the clamping means for the lower cutter-head support is exerted in a direction which is perpendicular to the direction of its adjustment, and the clamping action is exerted simultaneously and to equal degree at the respective ends of the cutter-head support, so that a firm clamping action throughout the length of the cutter-head support and rigid positioning of the cutter-head support may be effected without disturbance of adjustment. For aiding in preventing disturbance of adjustment I provide a pluri-part cutter-head support, the parts of which are in superposed relation, and connect the adjusting means with the lower of said parts and the clamping means with the upper of said parts, thereby further removing the clamping means from positive action upon the adjusting means.

Having thus fully described my invention, what I claim as new and desire to secure by Letters Patent, is:

1. In a wood planing machine, the combination, with a frame and a cutter-head arranged for operating on the under side of the material, of a pluri-part support for said cutter-head, the parts of said pluri-part support being superposed and having guiding means therebetween for shifting of an upper one of said parts on a lower one of said parts parallel to the axis of said cutter-head, adjusting means having adjusting connection with a lower one of said parts for adjusting said plurality of parts up and down, and means between said frame and an upper one of said parts for clamping said last-named part rigidly to said frame.

2. In a wood planing machine, the combination, with a cutter-head arranged for operating on the under side of the material, of a support for said cutter-head, and means at each end of said support for adjusting said respective ends to elevation, and operating means for each of said last-named means arranged for independently adjusting

each of said ends to elevation, and means for clamping said operating means together for simultaneously adjusting both said adjusting means by operation of either of said operating means.

3. In a wood planing machine, the combination, with a cutter-head arranged for operating on the under side of the material, of a cutter-head support therefor, adjusting means at each end of said support for adjusting said respective ends to elevation, a hollow shaft having operative connection with one of said adjusting means, an operating shaft in said hollow shaft having operative connection with the other of said adjusting means, an operating part for operating each of said shafts independently, and means for clamping said shafts together for causing simultaneous operation of both said adjusting means.

4. In a wood planing machine, the combination with a cutter-head arranged for operating on the under side of the material, of a support for the same, an adjusting means for each end of said support, and operating means for said respective adjusting means comprising a hollow shaft having operative connection with one of said adjusting means for operating the same, a shaft in the bore of said hollow shaft having operative connection with the other of said adjusting means for operating the same, a hand-wheel on each of said shafts, a friction clutch between one of said hand-wheels and one of said shafts, and means on said last-named shaft acting to move said last-named hand-wheel endwise for engaging said clutch and thereby clamping said shafts together.

5. In a wood planing machine, the combination, with a cutter-head arranged for operating on the under side of the material, of a frame, a support for said cutter-head, said frame and support having vertical guide-faces therebetween parallel to the axis of rotation of said cutter-head, means at each end of said support for independently adjusting said respective ends to elevation on said guide-faces, and pin and slot guide connection extending vertically between said frame and support across the guide-faces between said frame and support for guiding said support up and down in said frame and for tilting thereof in said frame and positioning said support in said frame in directions parallel to the axis of rotation of said cutter-head.

6. In a wood planing machine, the combination, with a frame, and a cutter-head arranged for operating on the under side of the material, of a cutter-head yoke in which said cutter-head is journaled, a saddle under said yoke, said yoke and saddle having guiding means therebetween for shifting said yoke on said saddle parallel to the axis

of rotation of said cutter-head, said frame and said saddle and yoke provided with vertical coacting guide-faces parallel to said axis, and independent adjusting means 5 for each end of said saddle for up and down adjustment thereof, said saddle and frame having pin and slot guide connection therebetween extending vertically for positioning said support in said frame in directions 10 parallel to said axis, and arranged for up and down and tilting movement of said saddle between said guide-faces on said frame, and oppositely acting wedge clamps coacting with one of said guide-faces on said 15 yoke, for the purpose described.

7. In a wood planing machine, the combination with a frame, and a cutter-head arranged for operating on the under side of the material, of a support for said cutter-head, means for adjusting said support to elevation, and means for clamping said support in adjusted positions comprising oppositely acting wedges located between said frame and support, and an operating part for said wedges having oppositely operating connections with said wedges:

8. In a wood planing machine, the combination, with a frame, and a cutter-head 30 arranged for operating on the under side of the material, of a support for said cutter-head, said frame and support having coacting vertical guide-faces therebetween parallel to the axis of rotation of said cutter-head, means for adjusting said support parallel to said guide-faces, means for clamping said support in adjusted positions comprising spaced-apart wedges between said frame and support having wedge-faces 35 at that side thereof distanced from said support, said wedge-faces slanting in opposite directions, wedge parts coacting therewith, said wedges provided with clamp faces parallel to said guide-faces at that 40 side thereof adjacent to said support, and a screw-rod having oppositely threaded connections with said respective wedges, for the purpose described.

9. In a wood planing machine, the combination, with a frame, and a cutter-head 50 arranged for operating on the under side of the material, of a support for said cutter-head, said frame and support having coact-

ing vertical guide-faces therebetween parallel to the axis of rotation of said cutter-head, means for adjusting said support parallel to said guide-faces, means for clamping said support in adjusted positions comprising spaced-apart wedges between said frame and support having wedge-faces 55 at that side thereof distanced from said support, said wedge-faces slanting in opposite directions, wedge parts coacting therewith, said wedges provided with clamp faces at that side thereof adjacent to said support, and a screw-rod having oppositely threaded connections with said respective wedges, said wedges having movements parallel to the axis of said screw-rod, and the movements of said wedges into wedging relation being limited solely by said wedging actions.

10. In a wood planing machine, the combination, with a frame, and a cutter-head arranged for operating on the under side of the material, of a support for said cutter-head, said frame and support having coacting vertical guide-faces therebetween parallel to the axis of rotation of said cutter-head, means for adjusting said support 75 parallel to said guide-faces, means for clamping said support in adjusted positions comprising spaced-apart wedges between said frame and support having wedge-faces at that side thereof distanced from said support, said wedge-faces slanting in opposite directions, said frame provided with wedge-faces coacting therewith, said wedges provided with clamp faces at that side thereof adjacent to said support, and a 80 screw-rod having oppositely threaded connections with said respective wedges, said wedges having movements parallel to the axis of said screw-rod, the movements of said wedges into wedging relation being 85 limited solely by their wedging actions, and means for limiting endwise movements of said rod.

In testimony whereof, I have hereunto signed my name in the presence of two subscribing witnesses.

PETER A. SOLEM.
